HIGH-INTENSITY LAMP OR SIMILAR ARTICLE

Minoru Araki, Tokyo, Japan, assignor to Lloyd's Electronics International, a corporation of California

Original design application Jan. 10, 1966, Ser. No. 1,856.
Divided and this application June 20, 1966, Ser. No. 9,269

Term of patent 14 years

(Cl. D48—20)

FIG. 1.

FIG. 4.

FIG. 2.

FIG. 5.

FIG. 3.

FIG. 6.

FIGURE 1 is a side elevational view showing a high-intensity lamp incorporating my new design and shown in closed position;

FIG. 2 is a front elevational view thereof;

FIG. 3 is a rear elevational view thereof;

FIG. 4 is a side elevational view thereof but with the reflector housing moved to an operative position;

FIG. 5 is a top plan elevational view of the lamp and shown in the closed position; and

FIG. 6 is a side elevational view similar to FIG. 1 but showing a modified form of the present invention.

In the form of the invention illustrated in FIGS. 1 through 5, the central section of the high-intensity lamp is translucent. The ornamented base section in the form of the invention illustrated in FIG. 6 is translucent in its entirety; however, a central partition, indicated in dotted lines in FIG. 6, confines the passage of light through the upper part of the translucent base. Except for the placement of the switch and ornamentation, the form shown in FIG. 6 is otherwise similar to that shown in FIGS. 1 through 5.

This is a division of application Ser. No. D. 1,856, filed Jan. 10, 1966.

I claim:

The ornamental design for a high-intensity lamp or similar article, substantially as shown and described.
